UNITED STATES PATENT OFFICE.

CHARLES W. KENNARD, OF BALTIMORE, MARYLAND.

DESIGN FOR A CANE OR UMBRELLA HANDLE.

SPECIFICATION forming part of Design No. 22,721, dated August 22, 1893.

Application filed April 6, 1893. Serial No. 469,362. Term of patent 3½ years.

To all whom it may concern:

Be it known that I, CHARLES W. KENNARD, a citizen of the United States, residing at the city of Baltimore, in the State of Maryland, 5 have invented and produced a new and original Design for Umbrella or Cane Heads, of which the following is a specification, reference being had to the accompanying drawing, in which is shown an elevation of my design. 10 The essential feature of the design consists of the representation of a globe or sphere having depicted thereon different portions of the earth's surface. The poles of the globe are flattened, and from the lower flattened portion of the globe projects a ferrule having its 15

top and bottom provided with a fancy thimble or ring of greater diameter than the ferrule proper. Upon the upper flattened portion of the globe is arranged a representation of a building having two side wings, and a 20 center portion surmounted by a dome.

What I claim is—

The herein described design for umbrella or cane handles, substantially as set forth.

In testimony whereof I hereunto affix my 25 signature in the presence of two witnesses.

CHARLES W. KENNARD.
